CONTROL DEVICE

Charles Fallis, Park Ridge, Carl H. Mayer, Jr., Wilmette, and Arthur Rodgers, Northbrook, Ill., assignors to The Fire Guard Corporation, a corporation of Illinois
Filed July 21, 1964, Ser. No. 384,170
9 Claims. (Cl. 74—2)

This invention relates to an energy storing control device for providing a relatively large force in response to a small triggering force and more particularly, to such a device for actuating the valve on a fire extinguisher head assembly.

The proper design of control devices of the foregoing type entails several important considerations. It is necessary, of course, to store sufficient energy in the device to actuate the valve in question. Generally this involves no problem since a proper sized energy storing spring can be used and the device manually cocked with the necessary force. However, it is important that there be a very sensitive trigger means to release this stored energy which will only be actuated in response to a particular event, such as a sudden increase in temperature, and not responsive to any other exterior or environmental event such as could result from dropping the device, vibrations, etc.

It is also desirable in such a device that a means be provided for manually triggering the control. Towards this end, it is desirable to provide a manual control in which a positive force is necessary to operate the same so that inadvertent handling of the manual control will not result in unintentional release of the stored energy. The manual control accordingly should be designed to be much less sensitive than the thermal control. Moreover, such manual control should be operable from a remote location. Towards this end, cable assemblies, for example, have been proposed. However, with presently known cable assemblies, the direction in which the cable must be pulled has generally been fixed so that some limitation in the installation of the control device is present. In other instances, it may be desirable not to use any type of remote control and towards this end, it is important to be able to remove any such remote control and still use the device as a solely thermally responsive control.

Another important consideration in the design of a control device is to render it adaptable to different types of thermally responsive devices. For example, a diaphragm actuated structure is used in many instances, movement of the diaphragm being effected by expansion of gases due to a rapid temperature rise. The movement of the diaphragm in turn is designed to trigger the device. On the other hand, there may be provided electrically operated thermostats at remote locations, the signal therefrom serving to actuate a solenoid. Thus, a different type of connection would ordinarily be necessary to operate the control device. It is preferable to avoid any changes in the device when used with different controls.

With all of the foregoing in mind, it is a primary object of this invention to provide an extremely versatile control device adaptable to various forms and combinations of triggering devices responsive to fluid pressure pulses, electric current, remote cable actuation and the like.

More particularly, it is an object to provide a control device which will provide a large actuating force in response to a small triggering force in such a manner that only certain elements will serve to trigger the device and other environmental events such as shock, vibration, etc. will not trigger the device.

2

Another important object is to provide a novel manually operable cable assembly means to effect manual triggering of the device from a remote location and from any desired direction.

Still another object is to provide a unique trigger control for control devices responsive to thermally operated structures of either the diaphragm type or electricaly operated type, or stored pressure type.

Briefly, these and many other objects and advantages of this invention are attained by providing a housing including an actuating rod protruding from one end. This rod is arranged to move from a raised set position to a lowered released position to provide the desired large actuating force to operate a fire extinguisher head assembly or any other equivalent valve structure. The inner end of the rod within the housing terminates in a coupling eye structure mounted to a disc in turn eccentrically secured to a shaft. The arrangement is such that rotation of the shaft will serve to cam the eye from a lower position to an upper position to cock or store energy within the device. Towards this end, there is provided a strong compression spring which is compressed upon movement of the actuating rod from its lower or most extended position to its retracted position. By using an eccentric arrangement movable towards an over-center position, a large amount of energy may be stored and yet the required force to release this energy approaches zero as the eccentric disc approaches the over center position. This disc includes a laterally extending latch arm which is adapted to be engaged by a pivoted trigger element. By adjusting the device such that positioning of the eccentric disc is just slightly to one side of the over center position, a very small force is exerted on the trigger element. On the other hand, the pivoting movement of the trigger element to release the latch arm to permit the latch arm and disc to rotate, will result in the release of the energy stored within the compression spring.

Other important features of the invention relate to the provision of a novel cable actuator assembly adapted to operate the trigger element when a cable is pulled and so mounted to the housing that the direction of pull may be varied as desired. Further, the housing includes a coupling adapted to receive either a diaphragm type thermal control, electrically operated thermostat solenoid structure, or pressure operated control. In any event, the trigger element is responsive to a movable member so that the adaptation of the diaphragm type, solenoid type or pressure type of thermal control may readily be achieved.

A better understanding of the improved control device of this invention will be had by now referring to a preferred embodiment thereof as illustrated in the accompanying drawings in which:

FIGURE 1 is a perspective view of the control device of this invention; and

FIGURE 2 is an enlarged cross section of the device taken generally in the direction of the arrows 2—2 of FIGURE 1.

Referring first to FIGURE 1, the device comprises a housing 10 including a lower coupling nut 11 and an actuating rod 12. The lower end of the rod 12 is visible in FIGURE 1 as protruding from the coupling nut 11. When the actuating rod 12 is in a raised position within the housing, energy is stored and when the device is triggered, the actuating rod moves from its raised to a lowered released position to provide the desired large magnitude force to operate auxiliary valves and the like.

Several means are provided for intentionally triggering the structure to release the energy stored within the housing 10. The most important of these comprises a thermally responsive device in the form of a diaphragm

casing 13 connected through a flexible pressure conduit 14 to a closed volume 15. The closed volume 15 may be disposed in any area in which a fire is liable to break out. The design is such that a rapid or extraordinary rise in temperature will result in a rate of expansion of the gas within the closed volume 15 sufficient to move the diaphragm within the casing 13 in a direction to trigger the structure in the device 10. With the device coupled to the top of a fire extinguisher head assembly by means of the coupling nut 11, the resulting downward movement of the actuating rod 12 will trigger the fire extinguishing device. A small air bleed is provided from the closed volume 15 so that normal environmental temperature changes will not move the diaphragm to trigger the structure within the housing 10.

To provide manual remote control of the triggering, there may be provided, for example, a cable actuator assembly 16 including first and second cables 17 and 18 extending in opposite directions therefrom. The arrangement is such that pulling on either of the cables 17 or 18 will serve to trigger the structure within the housing 10. In accordance with a further feature, the cable actuating assembly 16 may be swivelly mounted to the top of the housing 10 so that the direction of pull of the cables may be changed as desired.

Still another control may be provided in the form of a manually pivotable lever 19 normally locked against movement to the housing 10. However, removal of the locking key 19' to permit rotation of the manual lever 19 will enable the device to be triggered by moving the lever.

Except for the foregoing means for triggering the structure within the housing 10, it is not possible to otherwise actuate the device. Thus hammering or dropping or general vibrations exerted on the housing 10 will not release the energy stored therein.

After triggering, the device may be reset by rotating a center shaft 20. This operation as well as other features of the invention will be better understood by now referring to the enlarged cross-section of FIGURE 2.

Referring first to the lower portion of FIGURE 2, there is provided an integral fitting 21 to which the nut 11 is rotatably keyed and which terminates at its upper end within the housing 10 in an inturned flange 22. This flange supports the upper end of a compression spring 23 serving as the energy storing medium for the device. The lower end of the compression spring 23 seats on an annular stop 24 secured to the actuating rod 12. An annular guide 25 for the lower end of the rod is secured to the fitting 21 as shown. The arrangement is such that the nut 11 may be threaded over the upper nipple portion of a fire extinguisher head assembly so that downward movement of the actuating rod 12 from the solid to the dotted line position transfers the stored energy to actuate the fire extinguisher.

The movement of the actuating rod 12 is achieved by mechanism in the central portion of the housing 10. This mechanism includes an eye structure 26 threaded to the upper end of the actuating rod 12 and locked by set screw 27. The eye 26 defines a central opening 28 including an inner bearing race 29. A disc 30 is rotatably mounted by bearings 31 within the race 29 as shown. The disc 30 is eccentrically connected to the shaft 20 which in turn is rotatably mounted to the housing 10. A latch arm 32 extends laterally from the disc 30.

With the foregoing arrangement, it will be clear that rotation of the shaft 20 will serve to move the disc 30 from a position in which its center is below the shaft 20, as shown in dotted lines, to a position in which its center is above the shaft 20 as shown in solid lines. In the particular solid line illustration of FIGURE 2, the various elements are in their set or cocked position in which the actuating rod 12 is in its set raised position. If the disc 30 is free to rotate, and assuming that the center of the disc 30 is slightly to the left of a vertical line passing

through the shaft 20 so as not to be quite in an over center position, the disc 30 will rotate in a counterclockwise direction until its center is below the shaft 20 to assume the dotted line position. In this position, the actuating rod 12 is in its lowered released position. Thus, in setting or cocking the device, the shaft 20 is rotated in a clockwise direction until the latch arm 32 assumes the solid line position shown.

A trigger means including a trigger element 33 pivoted intermediate its ends at 34 is provided with one end terminating in a roller 35 constituting an engaging portion adapted to engage under the end of the latch arm 32. The arrangement is such that the engaging force exerted by the latch 32 on the roller 35 is in a direction in line with a straight line drawn through this engaging portion and the center pivot 34. Thus, pivoting movement of the trigger element 33 in a counterclockwise direction will initially move the engaging end roller 35 in a direction at right angles to the force exerted by the latch arm 32. By employing the roller 35, the degree of force needed to move the trigger element 33 from under the latch arm 32 can be made extremely small. Thus only a very small triggering force is required to release the energy stored in the device. This triggering force may be further decreased as a consequence of the eccentric construction wherein the closer the eccentrically mounted disc 30 is brought to an over center position, the less will be the force exerted by the latch arm 32 on the trigger element 33.

In order to control the sensitivity of the device, the trigger element 33 is provided with a trigger spring 33' secured between the element and the housing as shown. This spring may take the form of a hair spring structure and serves to bias the trigger element such that the roller 35 is urged under the latch arm 32 to prevent any inadvertent releasing of the latch arm. The force exerted by the spring 33' may be initially adjusted so as to require a given force to be exerted on the lower end 36 of the trigger element to effect counterclockwise rotation and trigger the device.

The diaphragm casing 13, as shown in enlarged cross section in FIGURE 2, is so positioned that the lower end 36 of the trigger element 33 will be engaged by a movable member 37 connected to the diaphragm 38. The other side of the diaphragm in turn is in communication with the closed volume 15 illustrated in FIGURE 1 through the conduit 14 by means of a coupling cylinder 39. The lower end of the cylinder 39 includes a small air bleed 40 so that slow rates of change of pressure within the closed volume will not move the diaphragm 38 but only a sudden change in pressure as would be caused by a rapid temperature rise is effective to actuate the diaphragm.

From the foregoing description, the operation of the components described thus far will be clear. Thus, a rapid rise in temperature to move the diaphragm 38 to the right and thus move the movable member 37 to the right will serve to rotate the trigger element 33 in a counterclockwise direction causing the roller portion 35 to disengage from under the latch arm 32. The latch arm 32 and disc 30 are thus free to rotate in a counterclockwise direction to assume the dotted line position shown and result in the movement of the actuating rod 12 from its solid to dotted line position. This movement of the actuating rod will then effect any desired function such as turning on a fire extinguisher. In this regard, it is to be pointed out that rod 12 has a loose fit in flange 22 and in annular guide 25 to accommodate slight lateral movement of rod 12 as a result of the circular motion of eccentric 30 and eye structure 26.

In re-cocking the device, the shaft 20 is rotated in a clockwise direction as explained in conjunction with FIGURE 1 until the latch arm 32 rides past the trigger element 33 and the trigger element is free to snap under the arm 32 and support the same. If the movable mem-

ber 37 has been retracted, there is sufficient room for the lower end of the trigger element 33 to move, the end of the movable member 37 serving as a stop for the trigger element. The spring 33' as explained heretofore, biases the trigger element generally in the desired direction to engage under the latch arm 32.

Referring now to the upper portion of FIGURE 2, the cable actuator assembly will be described in detail. As shown, there is provided an actuating element in the form of an inverted L structure 41 pivoted at 42 and including one end portion 43 disposed beneath the center top portion of the housing 10. The other end portion of the inverted L is indicated at 44 and is adapted to engage the trigger element 33 adjacent its upper roller portion 35 upon rotation of the L about its pivot 42.

Thus, downward movement of the upper end 43 of the L will result in lateral movement to the left of the other end 44 thereby causing the trigger element to disengage from under the latch arm 32. A spring 41' is provided to bias the L shaped member in a direction to avoid bearing against the trigger element 33 unless an intentional force is applied to the upper end 43.

To provide an intentional force, the cable actuator assembly includes a plunger at 45 biased upwardly by a compression spring 46. The upper end of the plunger terminates against the mid-section of a slide member 47 including inwardly tapered surface walls defining conical surfaces 47a and 47b meeting in the central portion of the slide member. The arrangement is such that movement of the slide member 47 in either the left or right hand direction will result in one or the other of the surfaces camming the plunger 45 in a downward direction thereby engaging the end 43 of the L shaped member 41 and thus triggering the device.

The movement of the slide member 47 may be achieved by either one of the cables 17 or 18, the slide member itself being biased to a central position by suitable springs 48 and 49. By adjusting the forces exerted by the various springs such as the plunger compression spring 46 and the springs 48 and 49, the manual pull force on either one or the other of the cables may be adjusted to adjust the sensitivity of the triggering action by the cables.

A feature of the structure described in conjunction with the cable actuator assembly resides in the threading of the assembly in a threaded opening 50 and using an expandable type washer 50' such that the cable assembly housing may be rotated and yet a proper seal maintained over the opening. By this arrangement, and because of the symmetry of the plunger element 45 about the vertical axis A—A, the direction at which the cables 17 and 18 extend from the housing 16 may be varied as desired.

Another feature of the use of a threaded opening 50 resides in the ease with which the cable actuator assembly 16 may be completely removed and the opening 50 simply plugged by a suitable close-off cap.

By also providing a threaded opening 51 on the left side of the housing 10 for the diaphragm casing 13 and by positioning the trigger element 33 to be operated by a movable member concentric with this opening, a solenoid may readily be substituted for the diaphragm structure with the solenoid plunger performing the function of the movable member 37.

It will also be appreciated other triggering means well known in the art may be coupled to openings 50 and 51. Briefly, automatic triggering could be effected by a diaphragm, a thermostat actuated solenoid, or a pressurized piston activated by a fusible link cartridge operator. A manual remote means could comprise a cable actuator, solenoid (actuated by a push-button) or a pressure pulse from a push-pull station. Any of these devices could be coupled at either 50 or 51.

Thus, while only one specified embodiment of the invention has been set forth and described, it will be evident that various changes and substitution of equivalent elements may be effected by those skilled in the art with-

out departing from the scope and spirit of the invention. The improved control device is therefore not to be thought of as limited to the one embodiment set forth merely for illustrative purposes.

What is claimed is:

1. A control device for providing a large actuating force in response to a small triggering force comprising, in combination: a housing; an actuating rod having a lower end protruding from the lower end of said housing; a compression spring biasing said actuating rod from a raised set position to a lowered released position to provide said large actuating force, the upper end of said rod terminating in a coupling eye within said housing, said coupling eye having a central circular opening; a disc received within said circular opening and having a latch arm extending radially therefrom; a shaft eccentrically secured to said disc and mounted to said housing for rotation about an horizontal axis so that rotation of said shaft from a first position in which the center of said disc is below said shaft to a second position in which the center of said disc is above said shaft, moves said actuating rod from its released position to its set position to compress said compression spring; and a trigger means in said housing and including an engaging portion positioned under said latch arm to hold said shaft and disc in said second position, said trigger means being responsive to said triggering force to disengage said latch arm and release said disc so that said compression spring moves said actuating rod from its set to released position to provide said large actuating force.

2. A control device according to claim 1, in which said housing includes an upper opening receiving a cable actuator assembly, said cable actuator assembly including two cables extending in opposite directions from said assembly and a central plunger received in said opening and responsive to pulling of either one of said two cables to move downwardly into said opening; and a pivoted member in said housing responsive to downward movement of said plunger into said opening to actuate said trigger means.

3. A control device according to claim 2, in which said cable actuator assembly is mounted to said opening for swiveling movement so that said cables can be pulled from any desired direction.

4. A control device according to claim 3, in which said cable assembly includes a slide member having opposite ends connected to said cables respectively and radially inwardly tapered sidewalls meeting at the center of the member to define a pair of conical surfaces, said plunger being cammed in a downward direction by one of said conical surfaces upon sliding movement of said slide member in one direction and by the other of said conical surfaces upon sliding movement of said slide member in the other direction.

5. A control device according to claim 4, in which said housing includes a side opening receiving a thermally operated assembly including a movable member receivable through said side opening in a position to engage a portion of said trigger means, said assembly being responsive to a given rate of temperature increase to move said member inwardly to actuate said trigger means.

6. A control device according to claim 5, in which said thermally operated assembly includes a pressure diaphragm, one side of which is connected to said movable member and the other side of which is subjected to gas pressure in a closed volume, said closed volume having an air bleed such that only said a given rate of temperature increase will provide sufficient pressure from thermal expansion against said diaphragm to actuate said triggering means.

7. A control device according to claim 6, in which said trigger means comprises a trigger element pivoted intermediate its ends to said housing, one end of said element constituting said engaging portion, said device being positioned such that a straight line from said engag-

ing portion to its pivot is in the direction of force exerted by said latch arm on said engaging portion so that pivoting movement of said element initially moves said engaging portion at right angles to said direction to release said latch arm.

8. A control device according to claim 7, in which said movable member for said thermal assembly is positioned to engage upon movement the end of said trigger element opposite to its engaging end so that inward movement of said end results in the outward movement of 10 said engaging end to release said latch arm.

9. A control device according to claim 8, including a

trigger element spring connected between said trigger element and said housing for biasing said trigger element such as to urge said lower end into engagement with said movable member.
